DESIGN.

A. SKINNER.

STOVE.

No. 9.

Patented Sept. 14, 1843.

Des. 9

Alanson Skinner Brownsville, New York.
Letters Patent No. 9, dated September 14, 1843.

The Schedule referred to in these Letters Patent and making
part of the same. —

Be it known that Alanson Skinner of Brownsville in
the County of Jefferson and State of New York have produced
a new design for Cooking Stoves, which I denominate the North-
ern Farmers Stove, and I do hereby declare that the following
is a full and exact description of the same. Fig. 1. is a Proje-
ctrical view. Fig. 2. geometrical side elevation, in the drawings
which accompany this specification and form a part of the same.

The hearth plate (a) is of an oblong form the four corners
being rounded across the middle of its longest sides, the ash pit
is sunk in the rear away in the bottom of this ash pit there
is a circular aperture (a') into which a portable furnace (b) of
ordinary construction. The ash pit is covered with a sliding
hearth (a") and the aperture in the bottom of the ash pit is
also furnished with a circular cover to be put in at pleasure;
besides the sliding hearth (a") that entirely closes the
ash pit outside the door of the fire chamber, there is a
mother that may be substituted (see (a'') detached) which
has a circular hole through it that comes directly over the fur-
nace and serves for a boiler hole when requisite. The four
upright plates of the fire chamber (c) rest upon the hearth
plate (a) and are small enough to have said plate projecting
at the sides as well as in front.

In the front of the fire chamber are double doors and

at one or both ends, doors are also placed. The top (a) of this chamber is of the proper form to entirely cover it, and from the fire chamber behind this, continues out, being some-
what contracted at its sides and is sufficient deep beyond
the fire chamber for the reception of boilers; in this plate
over the fire chamber an oblong hole, is cut out, the ends
of which are semicircular, across which a bar, is fitted that
converts them into two circular holes on which boilers can
be put, or one boiler, may be made large enough to fill
the whole - Behind this is a similar hole over the
horizontal chamber (f), which is formed of this plate be-
yond the fire chamber and a bottom and side plates
(d') these side plates being connected with the side plate of the
fire chamber, the back plate only extending up to the cham-
ber (f) at the rear end of the above described top plate, two
pipes (e) lead up to an elevated oven (h) of the common
construction; in the back part of the horizontal chamber (f)
there is an opening for a smoke pipe (e') to be attached to
this may lead up and join with that from the oven be-
fore it enters the chimney thro' vertical hinged valves
shown by dotted lines at (g) Fig. 1 close the communi-
cation between the horizontal chamber (f) and the two pipes
leading to the oven, or the one carrying off smoke from behind.

What I claim as my invention and desire to secure
by letters patent is the above described design for a heating
stove as described and represented in the accompanying
drawing.
